ATTORNEY

UNITED STATES PATENT OFFICE.

BERNARD T. MESKER AND THOMAS O. ARBEGUST, OF ST. LOUIS, MISSOURI,
ASSIGNORS TO MESKER & BROTHER, OF SAME PLACE.

BUILDING-FRONT.

SPECIFICATION forming part of Letters Patent No. 460,478, dated September 29, 1891.

Application filed November 20, 1889. Serial No. 331,015. (No model.)

To all whom it may concern:

Be it known that we, BERNARD T. MESKER and THOMAS O. ARBEGUST, of St. Louis, Missouri, have jointly made a new and useful Improvement in Building-Fronts, of which the following is a full, clear, and exact description.

The improvement relates to vestibular building-fronts; and it consists in the means whereby such fronts can be readily and economically constructed, substantially as is hereinafter set forth and claimed, aided by the annexed drawings, making part of this specification, in which—

Figure 1 is a front elevation of a building-front embodying our improvement. Figs. 2, 3, and 4 are horizontal sections thereof, disclosing the same in the different positions of which it is capable of adjustment. Fig. 5 is an enlarged horizontal section showing the construction at one of the inner corners of the vestibule, and Fig. 6 is a similar view showing the construction at one of the outer corners of the vestibule.

A, Figs. 1 and 2, represents a building-front of the customary description, saving as it may be modified or supplemented by the improvement under consideration. The vestibule B is shown in full; but the main portion of the front and which contains the vestibule 30 is shown in parts C C only, as its nature is well understood.

D D represent the posts or columns at the outer corners, respectively, of the vestibule, and E E respectively represent the posts at the inner corners of the vestibule.

F F represent the vestibule-sashes at the sides, respectively, thereof.

G G represent the vestibule-doors, and H H the front sashes at the sides, respectively, of the vestibule.

The invention is carried out by making the vestibule adjustable, so that it can be widened and made shallower or be narrowed and deepened.

In Fig. 3 is represented a vestibule of a certain width, in Fig. 2 a vestibule narrower and deeper than in Fig. 3, and in Fig. 4 a vestibule yet narrower and deeper than that of Fig. 2 is disclosed. In the form shown in Fig. 4 the columns D D are brought nearer together, and in the forms shown in Figs. 2 and 3 they are placed farther apart than in Fig. 4. When the columns D D are thus brought nearer together, the front A is nar-

rowed, and when the columns are spaced farther apart the front is widened. This adjustability of the vestibule is accomplished as follows: d represents a stop, which is removably fastened to the post D in the form of the vestibule as disclosed in Fig. 2. The corner f of the sash F comes against the stop d, and the corner f' of the sash F against the back d' of the post D, and the front face f² of the sash F comes against the projecting edge d² of the side d³ of the post D, by which means the outer edge of the sash F is fixed in place. The opposite or inner edge of the sash F is held as follows: The post E, Figs. 1 and 4, like the post D, has a removably-attached stop e, against which the corner f³ of the sash F comes, and the corner f⁴ of the sash comes against the face e' of the post E, by which means the inner edge of the sash F is held in place.

In the form of the vestibule as shown in Fig. 4, the stop d is set farther away from the edge d², and the outer edge of the sash is held as before, between the stop and the edge d². The sash, however, is arranged at a different angle to the front. The inner edge of the sash is held, as before, between the stop e and the face e' of the post E.

In the form of the vestibule as shown in Fig. 3 the sash F is arranged, as shown, at a still different angle, and its outer edge and its inner edge are respectively held as before. The stop d is set nearer to the edge d² than in the form of the vestibule shown in Fig. 2, to suit the changed position of the sash.

In place of shifting the stop d different stops may be used—that is, with each new inclination of the sash a new stop may be used and attached to the post D to confine the sash.

We claim—

The combination of the posts D, having projecting edges d² and stops d, removably secured to back pieces d' in said posts, the distantly-arranged posts E, having removably-attached stops upon their inner sides, and the sashes adapted to engage said stops, substantially as set forth.

Witness our hands this 21st day of October, 1889.

BERNARD T. MESKER.
THOMAS O. ARBEGUST.
